US0D1097818S

(12) **United States Design Patent** (10) **Patent No.:** **US D1,097,818 S**
(45) **Date of Patent:** **** Oct. 14, 2025**

(54) **CONTAINER**

(71) Applicant: **MARY KAY INC.**, Addison, TX (US)

(72) Inventor: **Zachary Webb**, Addison, TX (US)

(73) Assignee: **MARY KAY INC**, Addison, TX (US)

(**) Term: **15 Years**

(21) Appl. No.: **29/900,281**

(22) Filed: **Aug. 18, 2023**

(51) **LOC (15) Cl.** **09-01**

(52) **U.S. Cl.**

USPC **D9/549**

(58) **Field of Classification Search**

USPC D9/434–435, 454, 500, 503, 516, 549,

D9/575, 682, 690–691; D28/76, 91.1

CPC ... A45D 34/00; A45D 34/02; A45D 2034/007

See application file for complete search history.

(57) **CLAIM**

The ornamental design for a container as shown and described.

DESCRIPTION

FIG. 1 is a top perspective view of a container showing my new design;

FIG. 2 is a top view of the container shown in FIG. 1;
FIG. 3 is a front view of the container shown in FIG. 1, the container being symmetrical about its vertical axis;
FIG. 4 is a bottom view of the container shown in FIG. 1; and,

FIG. 5 is a bottom perspective view of the container shown in FIG. 1.

The dashed lines in FIGS. 1–5 are included for the purpose of illustrating portions of the container that form no part of the claimed design.

1 Claim, 5 Drawing Sheets
